UNITED STATES PATENT OFFICE.

JOHN E. LAGERGREN, OF NEW YORK, N. Y., ASSIGNOR TO THE IKONOGRAPH COMPANY OF AMERICA, OF NEW YORK, N. Y., A CORPORATION OF NEW YORK.

DESIGN FOR A PROJECTING-LANTERN.

No. 39,446.

Specification for Design.

Patented Aug. 18, 1908.

Application filed March 16, 1908. Serial No. 421,580. Term of patent 7 years.

To all whom it may concern:

Be it known that I, JOHN E. LAGERGREN, a citizen of the United States, and resident of New York, in the county of New York and State of New York, have invented a new, original, and ornamental Design for Projecting-Lanterns, of which the following is a specification, reference being had to the accompanying drawing, forming part thereof.

The figure is a perspective view of a projecting lantern, showing my new design.

The design comprises the configuration of a body having a rectangular basis and two sides integral with an arched roof of substantially semicircular cross section. The

two remaining sides have each an arched top, corresponding to and abutting the roof of the body, and a circular opening, the opening of one of the same provided with a curved cover, and the other with a cone-shaped extension. An ornamental mushroom-shaped top crowns the arched roof of the body.

I claim:

The ornamental design for a projecting lantern, as shown and described.

JOHN E. LAGERGREN
